ARM AND TENSION LINK HOIST FOR
DUMP BODIES

Joseph M. Gwinn, Jr., Dearborn, Mich., assignor
to Gar Wood Industries, Inc., Wayne, Mich., a
corporation of Michigan

Application October 13, 1949, Serial No. 121,106

5 Claims. (Cl. 298—22)

1

This invention relates to hydraulically operated arm and link hoist mechanisms for raising the body of a dump truck to dumping position.

It is the principal object of the invention to provide an arm-type hoist mechanism which is more efficient than comparable systems heretofore known, thereby permitting the use either of operating cylinders of smaller diameter or lower operating pressures in the hydraulic system.

This object is accomplished by means of a hydraulically actuated linkage mechanism in which the moment arm of the hoisting force varies with the degree of body lift in about the same manner as the moment arm of the load. Thus, it is high, and in excess of those heretofore employed in comparable arm-type hoist mechanisms at the beginning of lift, and gradually decreases to low value, or zero, when the desired dumping angle is reached. It will be appreciated that by virtue of this characteristic the actual force delivered by the hydraulic cylinder is less at the beginning of the lift than heretofore, and, furthermore, is in proportion to the load and therefore relatively constant throughout the entire angle of body pivot. In terms of the hydraulic equipment which energizes the lifting force, this means that at the option of the designer the hydraulic cylinder may be reduced in diameter, thereby permitting a reduction in the weight of the unit and the body mounting height, or the hydraulic pressure reduced, thus reducing the cost and wear. In terms of the linkage structure, the lower and relatively constant lifting force means less highly stressed and more efficiently used elements.

The present design is such that it also has other desirable features. Among these are a high dumping angle and a low height in collapsed condition, the latter feature enabling the body and the center of gravity of the truck to be lowered.

Briefly, according to the invention, the hoist mechanism is arranged so that the link which connects the arm to the body and applies the lifting force to the body is stressed in tension so that it pulls the body upwardly. In comparable prior mechanisms this link was stressed in compression so that it pushed the body upwardly. This simple change produces the surprising and important benefits above mentioned. The design is also such that the link dead centers on the body pivot axis rather than on the fixed axis of the link or arm to which it is connected. By virtue of this feature, it is possible to control the oil pressure at the elevated position of the body, this being impossible with prior comparable designs wherein the pressure approached zero with an increase in the angle of lift.

2

A preferred embodiment of the invention is shown by way of illustration in the accompanying drawings in which:

Figure 1 is a perspective view of the improved hoist mechanism;

Fig. 2 is a side elevation of the improved mechanism;

Fig. 3 is a diagrammatic view of the linkage in lowered, intermediate, and dumping positions;

10 and

Fig. 4 is a diagram showing how the lever arms of load and the lifting forces and the oil pressure vary with the angle of tilt of the body.

The invention is shown applied to a dump truck 15 chassis 1 having a separately manufactured sub-frame 3 affixed thereto, the latter having journals 5 for pivotally receiving the trunnions 1 of the body 9 to establish a hinge connection therewith. The invention is preferably assembled as 20 a part of the sub-frame, but, obviously, may be connected directly to the chassis.

The improved hoist mechanism includes a pair of laterally spaced arms 13 that are fixedly interconnected by a tubular cross member 14 that is 25 provided with trunnions 17 by means of which the arms are pivoted on a common axis in journals 19 that are affixed to the sub-frame forwardly of the pivot connection 5—7 of the body 9. The web member 15, that is also secured to the 30 tubular member 14, is inclined upwardly or rearwardly from the axis of the arms 13 and at its upper end has a pivotal connection 21 with a fitting 23 that is rigidly affixed to the end of a piston rod 25 that extends rearwardly from the 35 pressure cylinder 27. The latter has a pivotal connection 29 with the sub-frame 3 and it will be noted that this connection is offset beneath the axis of the cylinder 27 and that the pivotal connection 21 of the rod to the web 15 is offset 40 above the axis of the cylinder. This double offset provides increased leverage and other advantages described and claimed in a copending application Serial No. 164,761, filed May 27, 1950, entitled "Offset Cylinder and Piston Rod Mounting for 45 Hydraulic Dump Bodies" of the present inventor. However, it will be understood that the present invention may be employed with pressure cylinders that are mounted in the conventional manner.

50 In the lowered position of the body 9 that is shown in Fig. 2, the arms 13 extend forwardly and upwardly from their fixed pivot connection 17—19 so that the upper ends thereof and of the web 15, as well as the upper side of the cylinder 27, 55 are just beneath the underside of the body. The upper end of each of the arms 13 is connected to

the body 9 by means of a pair of tension links 31 that are pivoted thereto at 33. The links 31 extend downwardly and preferably also rearwardly so as to achieve maximum collapse (minimum height) of the linkage in combination with a high dumping angle and most efficient operation. Pins 35 connect together the lower ends of the links and pivotally connect them to and between pairs of attachment plates 37 that are rigidly affixed to the underside of the body 9 and extend downwardly therefrom, the plates 37 being spaced so that they and stop plates 41, to be described hereinafter, fit within the side members of the sub-frame 3.

When it is desired to raise the body 9, the pressure cylinder 27 is energized by conventional means to force the rod 25 rearwardly. This pivots the web 15 and arms 23 rearwardly and also the arm-link pivots 33. There is a tendency for the pivots 33 to move away from the link-body pivots 35 but this is prevented since these pivots are interconnected by the links 31. The latter are therefore placed in tension and apply a lifting force in tension to the body 9 through the medium of attachment plates 37. The body is thus pulled upwardly instead of pushed, as heretofore.

Stops to provide positive limits to movement of the links 31 relative to the attachment plates 37 during upward movement are provided. These may comprise plates 41 that are located on the pins 35 and welded to the outside of the plates 37. They have rigid inwardly extending lugs 43, the upper faces of which abut the longitudinal sides of the links in the upper position, as shown in Fig. 1. As indicated in Fig. 3, the links 31 in the present embodiment describe an arc of approximately 180° about the pivots 33 and relative to the sub-frame 3, and in practically all modifications this arc will at least exceed 90° unless very low dumping angles are desired.

Fig. 4 shows the manner in which the moment arms relative to pivot 5-7 of the load and body 9 and of the lifting force applied by links 31 vary in accordance with the angle through which the body is elevated. The moment arm is, of course, the shortest distance to the line of force and, therefore, in the case of the gravity load which acts directly downwardly, varies more or less as the cosine of the sum of the angle of tilt and the initial angle of a line through the load center and the hinge 5-7. In the case of the lifting force, however, the manner in which its effective moment arm varies is necessarily more complicated since it depends upon three continuously changing lever arms, viz., (1) the lever arm of the cylinder force (the line of action of which passes through pivots 23 and 29) about arm pivot 17, (2) the lever arm of link 31 about pivot 17, and (3) the lever arm of link 31 about body hinge 5-7. Nevertheless, with the present design, the effective moment arm of the lifting force, which is equal to (1) $\times$ (3) / (2), follows the pattern of the load moment arm with the exception of the brief divergence during the first few degrees of tilt, as shown in Fig. 4. This latter is due to the inclination of link 31 and if it is desired to eliminate it, the link 31 should be vertical in the fully lowered position.

Lifting of the body 9 involves, of course, essentially a balance between the moment of the lifting force and the moment of the load about pivot axis 5-7. In the present design, the relationship between the moment arms of these two forces is relatively constant or at least they vary in the same direction, i. e., rapidly de-

crease with increase of angle of tilt. Since the moment arms are in relatively constant proportion, the forces involved are too. Thus, the force which the piston rod 25 must supply is relatively constant. Consequently, as evident from Fig. 4, the oil pressure in the cylinder 27 is relatively constant and the peak pressure is only a little greater than the mean pressure. It is, therefore, not necessary as in the past to inefficiently design the cylinder 27 and the linkage to withstand momentary high pressures and forces that are necessary to overcome a lack of moment arm. On the contrary, in this design, since the loads on the pressure-actuated means and linkage are relatively constant, they may be designed to operate at substantially full and most efficient capacity through the entire angle of tilt.

The low vertical height of the present hoist mechanism has already been mentioned, and it should also be noted that the present design also permits high dumping angles and control by design of the oil pressures involved. One of the limiting factors in prior arm-type hoist mechanisms has been that the lifting force dead centered on the arm pivot, such as would (but does not) occur if the line of force in link 31 passed through pivot 17-19. If this happened, the moment of the resistance to movement applied by the link 31 to the arm 13 would be zero and so, therefore, would be the oil pressure. Thus, in prior art hoists wherein the link dead centers first on the arm hinge, it is seen that inherently the oil pressure approaches zero as the body elevates to move the link toward dead center on the arm pivot. However, the mean oil pressure is independent of hoist design and a function of the work done in elevating the load. Hence, since the mean oil pressure is unchangeable, the low oil pressures obtained at one angle of tilt had, in the prior art designs, to be balanced by high oil pressures at another angle resulting in higher maximum oil pressures than necessary with the hoist of this invention.

In the present design, however, the mechanical advantage is progressively decreasing and the link approaches closer to dead center on the body hinge 5-7 than to dead center on the arm pivot 17-19. This is shown in Fig. 3. If the link 31 were to pass dead center on hinge 5-7, before the line of force of the gravity load reached dead center on the hinge 5-7, the lifting force would become ineffective and the moment of resistance applied to arm 13 infinite and so, therefore, would the oil pressure in cylinder 27. Thus, it is seen that the inherent tendency in the present design is for the oil pressure and link loads to approach infinity. This, of course, is easily avoided by so proportioning the linkage that the center of gravity of the load reaches dead center on the body hinge before the line of link 31 passes through the body hinge. In addition, the previously described lugs 43 positively prevent the link 31 from pivoting relative to the body far enough to assume the dotted line dead center position illustrated in Fig. 3. Control of the geometry of the design enables the designer to control the oil pressure at elevated positions, something which is not possible in prior designs.

The optimum proportions of the arm and link and the location and distances between the various pivot points, including the body hinge 5-7, depend to a large extent upon the angle through which the center of gravity of the load must

swing between its lowest position and the position in which it is located directly above the body hinge, this angle being often referred to as the load dead center angle. The proportions of the linkage shown in Fig. 3 (which is scaled from an actual embodiment) are the optimum proportions for a load dead center angle of approximately 63° and will lift the body through an angle of 60°. Those proportions will work fairly satisfactorily for load dead center angles between 50° and 60° and will operate, but less efficiently, for lower load dead center angles. They cannot be used at all to lift the body through an angle above 60° unless the load dead center angle is less than 63° so that the load will dead center on the body hinge before the link 31 dead centers on the body hinge. For any load dead center angle larger or smaller than 63° the optimum proportions may be determined by cut and try. All factors considered, optimum results with the present linkage are obtained when the linkage is proportioned to obtain an oil pressure curve similar to that of Fig. 4 which is calculated for an eight ton batch load under worst conditions, i. e., that part of the load behind the hinge 5-7 is dumped at about a 50° angle. The actual oil pressure curve is parallel but displaced upwardly from the curve of Fig. 3, due probably, to the effects of friction. It will be noted that the oil pressure is a maximum at the beginning of lift and at a point near the end of the lift, both values being approximately equal. To achieve that result which, of course, is related to the shape of the moment arm curve, the link 21 is inclined slightly when the body is in its lowest position, as shown in the drawings.

It will be observed that the angle of tilt before the link 31 dead centers on the body hinge increases as the length of the link 31 and as the angle of its forward inclination approaches zero (i. e., the horizontal) and decreases as the distance between the body hinge 5-7 and the arm hinge 17-19 increases. However, it is usually desirable to make the distance between the arms and body hinges a maximum so as to obtain the benefits of the increased mechanical advantage. It should be noted that the line of force in link 31 should not intersect the line of centers of the body and arm hinges when the body is in lowered position or the link will dead center on the arm hinge in the early stages of lifting and, furthermore, jamming difficulties may be encountered.

Those in the art will recognize other benefits and modifications of the invention, hence it is not intended to limit it to the foregoing description.

What is claimed is:

1. In a dump truck, the combination of a body having a pivotal axis, a rigid member extending downwardly from the body, an arm having a pivotal axis, when the body is in lowered position said arm extending from its pivotal axis toward the free end of the body and alongside the member but above the lower part of the member, a link pivoted at its upper end to the arm at a portion alongside the member and at its lower end to the lower part of the member, and means for applying a lifting force to the arm to pivot it upwardly and toward the body pivot about its own pivot whereby the link is stressed in tension.

2. The invention as claimed in claim 1 wherein the arm extends away from the body pivot and upwardly from its own pivot and the link extends downwardly and toward the body pivot from the arm but does not intersect the line of centers between the arm and body pivots.

3. The invention as claimed in claim 1 including a stop on the member for limiting pivotal movement of the link relative to the member.

4. In a dump truck, the combination of a body having a fixed pivotal axis, a rigid member extending downwardly from the body, an arm having a fixed pivotal axis spaced forwardly of the body axis when the body is in lowered position, said arm extending forwardly and upwardly from its pivotal axis and alongside the member but above the lower end of the member, a downwardly and rearwardly extending link pivoted at its upper end to the arm at a position alongside the member and at its lower end to the lower end of the member, means for applying a lifting force to the arm to pivot it upwardly and rearwardly about its fixed pivot whereby the link is stressed in tension and is pivoted upwardly and rearwardly upon the arm as the arm is pivoted, said link being arranged to first approach a dead center position on the body pivot rather than on the fixed arm pivot.

5. In a dump truck, the combination of a body having a fixed pivotal axis, two laterally spaced pairs of rigid attachment plates extending downwardly from the underside of the body and adapted to fit within the side frame members of the truck chassis or sub-frame, said plates in each pair having inwardly extending lugs the upper faces of which form limit stops, a pair of laterally spaced arms including a rigid cross piece having a fixed pivotal axis forward of the body pivot axis, when the body is in lowered position said arms extending forwardly and upwardly between said plates, downwardly and rearwardly extending pairs of links between each pair of plates and pivoted at their upper ends to the arms and at their lower ends to the plates, and pressure-actuated means connected to the cross piece for pivoting the arms upwardly and rearwardly about their fixed axis whereby tensile lifting forces are applied to the links and thus to the plates and body, during upward movement of the body said links describing an arc of approximately one hundred eighty degrees with respect to their lowermost position before abutting against said stops and said links being arranged to first approach dead center positions on the fixed body pivot rather than on the fixed arm pivot.
